KOPPERS COMPANY, OF PITTSBURGH, PENNSYLVANIA, A CORPORATION OF
PENNSYLVANIA.

COOKING RETORT OVEN.

1,402,272.

Specification of Letters Patent. Patented Jan. 3, 1922.

Application filed June 12, 1920. Serial No. 382,595.

To all whom it may concern:

Be it known that I, JOSEPH VAN ACKEREN, a citizen of the United States, residing in Pittsburgh, in the county of Allegheny and 5 State of Pennsylvania, have invented a new and useful Improvement in Coking Retort Ovens, of which the following is a specification.

This invention comprehends improvements of especial utility in the coking retort oven art; and also comprehends certain improvements applicable to coking retort ovens of the well-known Koppers cross-regenerative type exemplified in the patent to H. 15 Koppers No. 818033, dated April 17, 1906.

The invention has for one of its objects to incorporate in a coke oven, a novel and efficient system for equalizing the flow through the regenerators and to and from the flame 20 or combustion flues in the heating walls that are located in planes above such regenerators, with the result that the flow in the interior portions of the regenerators and the flues that are located in the interior of the 25 oven is equalized relatively to the flow in the less remote portions of the regenerators and the less remote flues, both of which adjoin the sides of the oven or battery. With this general object in view, the invention comprehends the provision of a novel system of 30 control of the flow through several portions of the regenerators and through several groups of flues, with individualized control of such flow to each portion of the regenerator and its corresponding group of flues. 35

The invention has for further objects such other improvements or advantages in construction and operation as are found to obtain in the structures and devices hereinafter 40 described or claimed.

In the accompanying drawings, forming a part of this specification, and showing, for purposes of exemplification a preferred form and manner in which the invention may be 45 embodied and practiced, but without limiting the claimed invention specifically to such illustrative instance or instances:

Fig. 1 is a view in perspective of a section of a coking retort oven or battery of a type 50 embodying features above specified and equipped with the improvements of the present invention, portions of the battery being broken away to illustrate the interior construction.

Fig. 2 is a fragmentary horizontal section

through the channels in the bottoms of the several regenerators and illustrating the novel channel arrangement.

Fig. 3 is a similar view through the pillar walls just above the longitudinally extending connecting channels.

The same characters of reference indicate the same parts throughout the several views.

In its present embodiment, the invention is incorporated in a coking retort oven or coke oven battery, having features of well-known Koppers cross-regenerative type, exemplified in the patent to H. Koppers hereinabove mentioned, which retort oven or battery includes in its construction crosswise-extending parallel heating walls constituted of series of vertical flame or combustion flues, elongated coking chambers or ovens intermediate the heating walls and parallel therewith, crosswise-extending regenerators located in planes beneath the planes of the coking chambers and heating walls and parallel therewith. For convenience, the present description will be confined to this use of the invention; features of construction are, however, readily susceptible of other valuable applications, and consequently, it is manifest that the scope of the invention is by no means confined to the specific use and specific embodiment herein described as an 85 illustrative example.

Referring to the drawings, there are illustrated views of a coke oven battery of the by-product type, such as has been hereinbefore mentioned, which embodies in its construction a plurality of crosswise elongated heating walls 11 and a plurality of intermediate crosswise elongated vertical coking chambers or ovens 12. The heating walls 11 form the side walls of the respective coking chambers 12, as shown more particularly in Fig. 1, and in the present instance are supported by the heavy supporting or pillar walls 13 extending crosswise of the battery and located as shown beneath the heating walls 11. These pillar walls collectively form the main support for the entire superstructure of the oven battery and are themselves supported firmly upon a flat mat or platform 14 which constitutes the subfoundation on which the entire battery rests.

The coal to be coked is charged into the several coking chambers or ovens 12 through charging holes 15 located in the top 16 of the oven battery and positioned directly 110

above the ovens or chambers 12, as shown in Fig. 1. These charging holes 15 are equipped with the usual removable covers, not shown, which are removed when charging any of the several ovens and placed in position to close the tops of the ovens during the entire coking operation. Heat for coking the charges of coal in the several ovens or chambers 12 is derived from the heating walls 11 which, as before mentioned, extend crosswise of the battery at the sides of the coking chambers. To accomplish this purpose, the heating walls are respectively, constituted of series 17 of vertical flame or combustion flues, constituting elongated chambers for the combustion of gaseous fuel in an atmosphere of highly pre-heated air. Gaseous fuel for each set of heating flues 17 is supplied through gas conduits or channels 18, there being a gas channel for each set of heating flues. The flues of each series are operatively disposed in two groups, each of about half the length of the heating wall and respectively on opposite sides of the center line of such wall, this disposition of the flues being for the purpose of reversing the direction of flow therein at each periodic reversal of the oven.

The gas channels 18 extend inwardly from opposite sides of the oven or battery, there being a pair of gas channels in the pillar wall below each heating wall, the inner ends of said gas channels terminating at the center line of such wall. Each gas channel is provided with a series of gas ducts or nozzles which respectively enter the bottoms of the series of flues on the same side of the center line as the aforesaid gas channel. While one group of flues is operating as upburning flues and is receiving a supply of fuel gas from the gas channel 18 located in the pillar wall beneath the heating wall, the other group of flues in the same heating wall is concurrently operating to direct the downflow from the first mentioned group of flues into the regenerators located below the downflow operating flues. The usual reversing connections are provided for turning on the flow of gas into the channels which supply the upburning flues and for cutting off the flow of gas into the gas channels 18 which communicate with the downdraft flues.

Each flue 17 has at its top a port or opening 19 for draft and the passage of combustion products or waste gas from the flames within the flues. These ports 19 open up into horizontal flues 20 formed in the heating walls and connecting together all the flues of each heating wall. The horizontal channels or flues 20 just mentioned serve to direct the exhaust gases issuing from the ports 19 of the upburning flues constituting one group into the similar ports 19 of the downburning flues on the opposite side of

the longitudinal dividing line hereinabove mentioned and constituting another group. The draft through the ports 19 may be regulated by means of the usual movable dampers or sliding bricks 21 positioned in the bottoms of the horizontal flues 20 and adapted to be reached by access flues 22 which extend from the top of the channels or flues 20 in each heating wall to the top 16 of the battery, there being an access flue positioned over each flame or combustion flue of each heating wall.

The crosswise regenerators 23 of the battery are located in planes below the planes of the aforesaid heating walls 11 and coking chambers 12 and in the present instance extend in parallelism beneath the coking chambers 12 between the pillar walls 13. Below the middle lengthwise line of the heating wall aforesaid, there is a partition 24, as shown in Fig. 1, which extends all the way up from the mat 14 of the battery to the bottom of the overlying coking chamber and from one end to the other of the pillar walls 13, such partition 24 corresponding in position to the line between the hereinbefore mentioned two groups of combustion flues in the heating wall thereabove. With this construction, there are thus formed below each coking chamber and crosswise of the battery, two end to end regenerators 23, the meeting ends of which are the partition 24 above mentioned. Each regenerator 23 is a chamber containing open brickwork commonly called checkerwork 100 and indicated at 25, with a system of distributing sole channels underneath or the checkerwork of each regenerator, the sole channel system constituting one of the features of the present invention as will herein-after appear. These regenerators 23 in alternation are heated by the combustion products that are exhausted from the flame or combustion flues hereinabove mentioned and then impart such heat to the air that, they feed into these flame flues.

The reversal in direction of flow through the several regenerators of the battery, and also through the flame or combustion flues of the heating walls with which the regenerators communicate, takes place crosswise of the battery in accordance with the mode of operation designated in the patent to Koppers above mentioned. For example, all of the regenerators 23 on one side of the partition 24 operate concurrently as inflow regenerators, while all of the regenerators on the opposite side of the partition 24 operate concurrently as outflow regenerators. On reversal by means of the usual reversing connections all of the regenerators which previously operated as inflow regenerators become outflow regenerators and concurrently all of the regenerators which previously operated as outflow regenerators

become inflow regenerators. It will be understood that the inflow operating regenerators deliver preheated outside air supplied through the air boxes 26 to the up-burning flues and that the outflow operating regenerators receive the products of combustion from the downdraft flues and convey such products of combustion to the waste gas tunnel 27 leading to the stack. The tops of the respective regenerators 23 communicate with the flues 17 by means of ducts 28, there being a series of such ducts connecting the top of each regenerator with its corresponding group of flues located on the same side of the central longitudinal line 24.

The present invention is chiefly concerned with the provision of a novel system for controlling the flow through the several regenerators and flues whereby the flow through the interior portions of the regenerators and those flues which are located in the interior portion of the battery is equalized with respect to the less remote portions of the regenerators and the less remote flues, both of which adjoin the sides of the battery. It is desirable to equalize the flow throughout each regenerator and throughout the entire group of flues with which it communicates, in order to obtain uniform heat conditions throughout the entire battery structure. Such equalizing of the flow is a problem of no inconsiderable difficulty, not only because of the great size of the regenerators themselves but also because of the fact that those flame flues which are located in the longitudinal central portion of the oven are more remote from the points where the air enters the regenerators than the flues adjoining the sides of the oven, and are also more remote from the stack tunnel 27 than the last mentioned flues. It is consequently necessary to vary the draft in these more remote flues somewhat in order to equalize the volume of flow entering those flues with that entering the flues which adjoin the sides of the battery and are consequently located nearer the points of supply or the points of discharge.

The above mentioned equalizing of flow throughout the regenerators and the flues is accomplished by the present invention in the following manner. The checkerwork of each regenerator is divided into a plurality of compartments 29 by means of vertical partitions 30 connecting together the pillar walls 13 on the opposite sides of such regenerator. Thus divided, each compartment of the regenerator checkerwork controls the flow through a subgroup of flues of the entire group of flues corresponding to and connected with such regenerator. An individual flow may thus be maintained in each compartment and the draft in the longitudinal-extending connection chan-

more remote portions of the regenerator and the more remote flues may thus be adjusted and controlled to equalize the flow in such remote regenerator portions and flues with respect to the other regenerator portions 70 and flues without disturbing the flow in those portions of the regenerator and flues which are nearer to the point of air supply or to the point of waste gas discharge.

As shown in the drawings, the series of 75 regenerators on each side of the battery are divided into groups, there being in the present instance eight regenerators parallel with each other in each group. Located in the bottom of each of such regenerators are 80 three crosswise-extending sole channels 31, which, however, extend to and open up into only one of the compartments 29 of their respective regenerators. Assuming that the three sole channels 31 in the bottom of the 85 regenerator at one end of the group of such regenerators extend to and open up into the innermost compartment 29 of that regenerator, the corresponding three sole channels 31 of the next adjacent regenerator extend 90 to and open up into the compartment next to the innermost compartment of their corresponding regenerator. Similarly, the three sole channels 31 of the other regenerators taken seriatim, extend respectively to and 95 open up into compartments 29 of their regenerators which are next less remote than the compartments 29 connected with the channels 31 of the preceding regenerators. The result is that the sole channels 31 of the 100 regenerator at one end of the group lead to the innermost compartment 29, whereas the sole channels 31 of the regenerator at the other end of the group lead to the outermost compartment 29, as shown in Fig. 2. It will 105 be noted that the outermost compartments 29 of all the regenerators are of much less depth than the other compartments of such regenerators.

Above the before-mentioned crosswise-extending sole channels 31 are longitudinally-extending connection channels 32. These connection channels 32 connect together all of the compartments of the several regenerators of each group of regenerators which are 115 of the same degree of remoteness in their respective regenerators. Thus all of the most remote compartments 29 of each entire group of regenerators are interconnected by means of three of such longitudinally-extending connection channels 32; the next remote series of compartments of the entire group of regenerators are similarly interconnected by three of such longitudinally-extending channels 32, and so on. It will be 120 noted, however, that the several compartments 29 in each group of regenerators that are the least remote from the side of the battery are interconnected by only two of said 125 channels 32. It will be 130

nels 32, because of the lesser depth of such compartments.

Each group of three crosswise-extending sole channels 31, of each group of regenerators, extends to the longitudinal connection channels 32 of the compartments with which such group of crosswise-extending sole channels connects. Thus the flow of the several compartments of one degree of remoteness 10 from the side of the battery in each group of regenerators may be controlled by the flow in a single group of crosswise-extending channels 31 independently of a series of compartments 29 of another degree of remoteness in the same group of regenerators, for the reason that said last mentioned series of compartments 29 are all fed by another group of crosswise-extending sole channels 31.

20 The groups of crosswise sole channels 31 of the several groups of regenerators in the battery assembly respectively extend to and are connected with the usual air boxes 26, provided with the usual lids 33 and the usual dampers 34, said lids and dampers being operable in series in alternation on the opposite sides of the battery for alternatively connecting the regenerators on one side of the battery with the outer air or with the 25 stack tunnel 27. In accordance with the invention each air box lid 33 is capable of adjustment independently of the others and likewise each damper 34. By an independent adjustment of the several air box lids 33 and a similarly independent adjustment of the several dampers 34 the inflow and outflow through the individual groups of sole channels 31 may be individually controlled and regulated. The usual reversing cables 35 30 are provided for closing all of the air box lids 33 or opening them simultaneously; there is also provided the usual reversing mechanism for simultaneously opening and closing an entire series of dampers 34 on 35 either side of the battery.

With the foregoing construction, coupled with the individual adjustability of the several air box lids 33 and the several outflow dampers 34, it is possible to regulate the 40 draft conditions in all parts of the oven or battery in a manner to equalize the flow in all parts of the battery, notwithstanding the different degrees of remoteness which different parts of the battery bear to the points 45 of air supply and the points of discharge of exhaust gases. For example, as the lid and damper of a single air box control the flow to the entire series of regenerative compartments 29 of the same degree of remoteness 50 of each entire group of regenerators, the draft in all of the regenerative compartments and to all of the flues with which such compartments communicate may be equalized and adjusted relatively to the 55 draft in another series of compartments of

a different degree of remoteness, so as to vary the draft in different portions of the oven in a way that will equalize the flow throughout the oven as a whole.

The invention as hereinabove set forth is 70 embodied in a particular form of construction, but may be variously embodied within the scope of the claims hereinafter made.

What I claim is:

1. In a coking retort oven, in combination: a plurality of coking chambers; heating walls contiguous to said coking chambers and respectively constituted of a series of combustion flues; regenerators located in planes below the planes of the coking chambers and the heating walls, the regenerators being arranged in series extending along opposite sides of the battery and the regenerators of each series being operatively disposed into groups containing as many regenerators as there are compartments in a regenerator, said regenerators respectively having checkerwork divided by partitions extending transversely of the regenerator into a plurality of compartments, each one of which communicates individually with a group of combustion flues of a heating wall; groups of connecting channels extending longitudinally of the battery and each group of such channels interconnecting all the aforesaid compartments of a like degree of remoteness, with respect to the side of the battery, of an entire group of regenerators; groups of sole channels extending crosswise of the battery and each group of such crosswise-extending channels leading to and connected with a group of the aforesaid longitudinally-extending channels; means for reversing the direction of flow through the regenerators, including their several groups of channels; and means for separately controlling the flow in both directions through each of such crosswise-extending group of channels; substantially as specified.

2. In a coking retort oven, in combination: a plurality of coking chambers; heating walls contiguous to said coking chambers and respectively constituted of a series of combustion flues; regenerators located in planes below the planes of the coking chambers and the heating walls, said regenerators respectively having checkerwork divided by partitions extending transversely of the regenerator into a plurality of compartments, each one of which communicates individually with a group of combustion flues of a heating wall; groups of connecting channels extending longitudinally of the battery and each group of such channels interconnecting all the aforesaid compartments of a like degree of remoteness, with respect to the side of the battery, of a plurality of regenerators; groups of sole channels extending crosswise of the battery and each group of such crosswise-extending channels leading to and con-

5 nected with a group of the aforesaid longitudinally-extending channels; means for reversing the direction of flow through the regenerators, including their several groups of channels; and means for separately controlling the flow in both directions through each of such crosswise-extending groups of channels; substantially as specified.

10 3. In a coking retort oven, in combination: a plurality of coking chambers; heating walls contiguous to said coking chambers and respectively constituted of a series of combustion flues; regenerators located in planes below the planes of the coking chambers and the heating walls, said regenerators respectively having checkerwork divided by partitions extending transversely of the regenerator into a plurality of compartments, each one of which communicates individually with a group of combustion flues of a heating wall; groups of connecting channels extending longitudinally of the battery and each group of such channels interconnecting all the aforesaid compartments of a like degree of remoteness, with respect to the side of the battery, of a plurality of regenerators; groups of sole channels extending crosswise of the battery and each group of such crosswise-extending channels leading to and connected with a group of the aforesaid longitudinally-extending channels; and means for separately controlling the flow through each of such crosswise-extending groups of channels; substantially as specified.

15 4. In a coking retort oven, in combination: a plurality of coking chambers; heating walls contiguous to said coking chambers and respectively constituted of a series of combustion flues; regenerators located in planes below the planes of the coking chambers and the heating walls, said regenerators respectively having their checkerwork divided into a plurality of compartments, each one of which communicates individually with a group of combustion flues of a heating wall, groups of channels extending longitudinally of the battery and each group of such channels interconnecting all the individual compartments of a like degree of remoteness, with respect to the side of the battery, of an entire group of regenerators; groups of channels extending crosswise of the battery and each group of such crosswise-extending channels leading to and connected with a group of the aforesaid longitudinally-extending channels; means for reversing the direction of flow through the regenerators including their several groups of channels; and means for separately controlling the flow in both directions through each of said crosswise-extending groups of channels; substantially as specified.

20 5. In a coking retort oven, in combination:

25 tion: a plurality of coking chambers; heating walls contiguous to said coking chambers and respectively constituted of a series of combustion flues; crosswise regenerators located in planes below the planes of the coking chambers and the heating walls and operatively disposed into groups, said regenerators respectively having their checkerwork divided into a plurality of regenerative compartments, each one of which communicates individually with a group of combustion flues of a heating wall, all the regenerative compartments of a like degree of remoteness from the side of the battery of an entire group of regenerators being connected together; and means located exteriorly of the oven for separately controlling the flow in each interconnected group of such compartments; substantially as specified.

30 6. In a coking retort oven, in combination: a plurality of coking chambers; heating walls contiguous to said coking chambers and respectively constituted of a series of combustion flues; regenerators located in planes below the planes of the coking chambers and the heating walls, the regenerators being arranged in series extending longitudinally along opposite sides of the battery and the regenerators of each series being operatively disposed into groups, said regenerators respectively including checkerwork divided by partitions extending transversely of the regenerator into a plurality of individual compartments, each one of which communicates individually with a group of combustion flues of a heating wall; groups of channels extending longitudinally of the battery and each group of such channels interconnecting all the individual compartments of a like degree of remoteness, with respect to the side of the battery, of an entire group of regenerators; groups of channels extending crosswise of the battery and each group of such crosswise-extending channels leading to and connected with a group of the aforesaid longitudinally-extending channels; means for reversing the direction of flow through the regenerators including their several groups of channels; and means for separately controlling the flow in both directions through each of said crosswise-extending groups of channels; substantially as specified.

35 JOSEPH VAN ACKEREN.
